Radio Corporation of America, a corporation
of Delaware

Application September 21, 1948, Serial No. 50,302

9 Claims. (Cl. 315—27)

1

This invention relates to wave forming systems and more particularly to television horizontal or line deflection systems.

Television horizontal magnetic deflection circuits normally employ high vacuum type tubes to generate the sawtooth wave currents required for deflection of the cathode ray beam used in the image scanning operation. Because of the possible gain in efficiency in such magnetic generators employed in television systems, attempts have often been made to use gas discharge tubes, such as those known in the art as "thyatrons." However, the de-ionization time of thyatrons makes such tubes practically inoperative when used in conventional television horizontal deflection circuits.

In my co-pending United States application entitled "D. C. Transfer Systems," Serial No. 730,852, filed February 25, 1947, there is shown and described a method and means whereby the grid controlled thyatron may be made to conduct during the short or retrace interval when an arbitrary conduction wave may be used, and the energy then stored may be utilized during the entire long or traced interval to produce the desired wave shape. In my co-pending application referred to immediately above, there is also provided current and voltage wave shapes during the retrace or short interval such that proper conditions are established for the de-ionization of the thyatron immediately following the conduction interval, thus taking advantage of the large short-time currents available from the thyatron and allowing the de-ionization to take place during the longer trace interval when it will not interfere with the desired circuit operations.

According to this invention there is provided a circuit arrangement utilizing an auto-transformer to obtain voltage gain and there is provided an arrangement whereby the grid controlled thyatron may be made to conduct during the short or retrace interval when an arbitrary conduction wave shape can be tolerated.

The primary object of this invention is to provide for improved and more efficient television horizontal or line magnetic deflection.

Other and incidental objects of the invention will be apparent to those skilled in the art from a reading of the following specification and an inspection of the accompanying drawing which illustrates schematically one form of this invention.

The operation of this invention may perhaps best be explained by referring briefly to sawtooth wave forming theory.

2

If a D. C. potential is connected across an inductance, the current in the conductor builds up to a final value which is determined by the D. C. input voltage and the D. C. resistance value of the inductance. The build-up of current is gradual because of the counter-E. M. F. generated by the inductance. Immediately upon the starting of the flow of current through the inductance, magnetic lines of force move out, cutting the turns of wire in the inductance, building up a counter-E. M. F. which is opposed to the E. M. F. of the D. C. source. This opposition causes a delay in the time it takes the current through the inductance to build up to a maximum and uniform value. When the source of power is disconnected, the lines of force about the inductance collapse again cutting the turns of the inductance and building up an E. M. F. which tends to prolong the current flow to the inductance. This action causes the sawtooth wave which is utilized in the scanning operation.

It is upon this basic theory that the present invention operates.

Turning now in detail to the drawing there is shown a cathode ray tube 1 which may, for example, take the form of the well-known kinescope with magnetic type deflection accomplished through vertical deflecting coils 3 and horizontal deflecting coils 5.

Details of construction and operation of tube 1 are not given here in view of the fact that the employment of this invention is not particularly limited to any specific form thereof. Typical kinescopes are well shown and described in the television art.

The switching or keying which is necessary to provide sawtooth waves is accomplished in driver tube 7 which, as illustrated, takes the form of a gas discharge device such as a thyatron which includes a control electrode 9 and an auxiliary electrode 11. In the operation of a thyatron the control electrode 9 is adapted to receive synchronizing pulses.

An auto-transformer 13 includes a terminal 15 which is common to both the primary and secondary of the auto-transformer 13. There is also included an uncommon terminal 17 which is connected to the anode of tube 7. A second uncommon terminal 19 is connected through a condenser 21 to a diode 23.

A parallel connected circuit including resistance 25 and capacity 27 is connected to terminal 15 of the auto-transformer 13 and the cathode of diode 23.

Thyatron tube 7 is supplied with an operat-

ing anode potential through the primary of auto-transformer 13 and through the resistance capacity circuit from terminal 29 to which there is applied a positive potential of the order, for example, of 300 volts.

A circuit output terminal is also provided at the junction of condenser 21 and the anode of diode 23. This circuit output terminal may be connected as illustrated to the horizontal deflection coils 5 of kinescope 1. The other terminal of deflection coils 5 is connected to a point of fixed potential such as ground, through a condenser 31.

The choke coil 33 having a high inductance value as compared to the inductance of the deflection coils 5 is connected between the source of positive potential at terminal 29 and the junction between condenser 21 and the anode of diode 23. Among its other functions choke coil 33 permits centering of the scanning beam without resorting to auxiliary circuit arrangements to compensate for the direct current component flowing in the circuit from power supply terminal 29.

The operation of the circuit shown in the drawing may best be explained by considering the driver tube 7 and the diode 23 as switches. For the purpose of the description of the operation of the circuit let it be assumed that no power has been supplied to the circuit and that for the initial part of this explanation none of the condensers of the circuit contain a charge.

Assume now that a supply voltage of 300 volts is applied to terminal 29 and positive synchronizing pulses are applied to control electrode 9 of the thyratron or driver tube 7.

Upon application of a positive synchronizing pulse to control electrode 9 of driver tube 7, tube 7 becomes conducting, driving point 17 of transformer 13 to the ionization potential of tube 7 which is very close to ground potential. This drop in potential at point 17 causes terminal 19 of auto-transformer 13 to go to a negative potential and extinguish tube 7. In view of the fact that diode 23 will be non-conducting when its anode is negative with respect to its associated cathode, a surge of current will be formed in the choke coil 33 and the deflecting coils 5. By reason of this surge of current in the inductances of coils 33 and 5, energy will be stored therein which, in accordance with the well known fundamental theory of inductances, will oscillate to cause on the other half of its cycle a highly positive voltage on anode of diode 23. This positive voltage on the anode of diode 23 will cause diode 23 to become conductive and a rectified voltage will then charge condenser 27 with a polarity as indicated by the signs and the relative potentials indicated in the drawing.

It is probably necessary that the time of several synchronizing impulses will be required to charge condenser 27 to its operating potential. It is also important in the understanding of the operation of this circuit to realize that although it might appear that the upper side of condenser 27 would be at a lower potential than the lower side by reason of the fact that it is connected in series with the plate circuit of driver tube 7, this is not the case because of the action taking place as described above. It is, of course, true that the driver tube 7 does tend to draw current from the circuit involving condenser 27. The quantity of current drawn from this circuit in this manner is, however, small as compared to the current drawn through the circuit including the inductance 33.

Now that condenser 27 has received its charge

as illustrated, the normal operation of the circuit will be explained.

Upon the application of a positive synchronizing pulse to control electrode 9 of driver tube 7, terminal 17, as has been explained above, will be dropped in potential to substantially ground potential. It follows then that the anode of diode 23 will be driven negative to open the diode 23 thus causing the magnetic field in choke coil 33 and deflection coils 5 to collapse. This collapsing corresponds to the short retrace time in the scanning cycle. The flywheel effect in the inductance of transformer 13 will cause point 17 to continue pass ground potential in a negative direction to extinguish the driver tube 7. Terminal 19 will then in its oscillation return to a positive potential and cause diode 23 to conduct by reason of the fact that the anode of diode 23 exceeds in a positive direction the potential of its associated cathode.

During the time that diode 23 is conducting a substantially constant direct current potential which is stored in the condenser 27 will be impressed across the choke coil 33 and the deflection coils 5 to cause a linear deflection of the cathode ray beam in accordance with well known sawtooth wave forming characteristics of an inductance.

At the arrival of the next positive synchronizing pulse, the driver tube 7 is again made conducting and the cycle repeats.

The difficulty in extinguishing gas tube 7 may be overcome by increasing the time during which its anode is negative with respect to its cathode. In the circuit shown this may be accomplished by constructing auto-transformer 13 in such a manner that it has leakage inductance or adding a small inductance between terminal 17 and the anode of the driver tube.

It will be seen that the source of positive voltage may be applied to common terminal 15 of auto-transformer 13, but by including the circuit consisting of condenser 27 and resistor 25 in the anode supply circuit of tube 7, an increased voltage may be had thus increasing the efficiency of operation of the circuit.

Although diode 23 is shown as a gas diode it may also take the form of the conventional high vacuum diode.

Although it is not intended that the employment of this invention must necessarily be limited to the generation currents for magnetic deflection of cathode ray beams for use in television systems, its operation in that regard provides for improved and more efficient deflection.

What is claimed is:

1. A sawtooth wave generator comprising, in combination, a transformer having an input and output circuit, said transformer also having a terminal connected common to said input and output circuits, an uncommon terminal for said input circuit and an uncommon terminal for said output circuit, a switching device connected between said uncommon input terminal and a point of fixed potential, said switching device consisting of a discharge device, a parallel connected resistance and capacity circuit, a source of potential positive with respect to said fixed potential connected to said common terminal through said parallel connected resistance and capacity circuit, a condenser connected to the uncommon output terminal of said transformer, a diode tube having a cathode, said diode connected between said common terminal of said transformer and said condenser terminal opposite to the termi-

nal connected to said uncommon output terminal, the cathode of said diode being connected to said common terminal, a choke coil connected between said source of positive potential and the junction of said condenser and diode tube, a circuit output terminal at the junction of said condenser and diode tube, and means for closing said switching device periodically for relatively small time intervals.

2. A sawtooth wave generator comprising, in combination, an auto-transformer having an input and output circuit, said auto-transformer also having a terminal common to said input and output circuits, an uncommon terminal for said input circuit, and an uncommon terminal for said output circuit, a thermionic switching device connected between said uncommon input terminal and a point of fixed potential, a parallel connected resistance and capacity circuit, a source of potential positive with respect to said fixed potential connected to said common terminal through said parallel connected resistance and capacity circuit, a condenser connected to the uncommon output terminal of said transformer, a diode tube having a cathode, said diode connected between said common terminal of said auto-transformer and the terminal of said condenser opposite to the terminal connected to said uncommon output terminal, said diode cathode connected to said common terminal, a choke coil connected between said source of positive potential and the junction of said condenser and diode tube and a cathode ray tube deflection coil, said cathode ray tube deflection coil connected serially with a second condenser, said serially connected deflection coil and second condenser connected between a point of fixed potential and the junction of said condenser and diode tube, and means for closing said switching device during the snap-back time of the sawtooth wave.

3. A sawtooth wave generator comprising, in combination, an auto-transformer having an input and output circuit, said auto-transformer also having a terminal common to said input and output circuits, an uncommon terminal for said input circuit, and an uncommon terminal for said output circuit, said auto-transformer having a step-up turn ratio between its primary and secondary circuits, a gaseous discharge tube switching device connected between said uncommon input terminal and a point of fixed potential, a parallel connected resistance and capacity circuit, a source of potential positive with respect to said fixed potential connected to said common terminal through said parallel connected resistance and capacity circuit, a diode having a cathode and an anode, a condenser connecting said diode and said common terminal of said auto-transformer, said diode cathode connected to said common terminal, a choke coil connected between said source of positive potential and the junction of said condenser and diode and a cathode ray tube deflection coil, said cathode ray tube deflection coil connected serially with a second condenser, said serially connected deflection coil and second condenser connected between a point of fixed potential and the junction of said condenser and diode, and means for closing said switching device periodically for relatively small time intervals.

4. A sawtooth wave generator comprising, in combination, an auto-transformer having an input and output circuit, said auto-transformer also having a terminal common to said input and output circuits, an uncommon terminal for said

input circuit, and an uncommon terminal for said output circuit, said auto-transformer having a step-up turn ratio between its primary and secondary circuits, a switching device connected between said uncommon input terminal and a point of fixed potential, said switching device consisting of a gaseous discharge tube, a parallel connected resistance and capacity circuit, a source of positive potential connected to said common terminal through said parallel connected resistance and capacity circuit, one terminal of a condenser connected to the uncommon output terminal of said transformer, a diode connected between said common terminal of said auto-transformer and the other terminal of said condenser, a choke coil connected between said source of positive potential and the junction of said condenser and diode, a cathode ray tube deflection coil, said cathode ray tube deflection coil connected serially with a second condenser, said serially connected deflection coil and second condenser connected between a point of fixed potential, and the junction of said condenser and diode, and a source of synchronizing pulses for initiating the conduction of said gaseous discharge tube at the end of the long trace of the sawtooth wave.

5. A sawtooth wave generator comprising, in combination, an auto-transformer having an input and output circuit, said auto-transformer also having a terminal common to said input and output circuits, an uncommon terminal for said input circuit and an uncommon terminal for said output circuit, said auto-transformer having a step-up turn ratio between its primary and secondary circuits, a discharge switching device connected between said uncommon input terminal and a point of fixed potential, said switching device consisting of a gaseous discharge tube, means for periodically firing said gaseous discharge tube, a parallel connected resistance and capacity circuit, a source of potential positive with respect to said fixed potential connected to said common terminal through said parallel connected resistance and capacity circuit, a diode having an anode, a condenser connected between said uncommon output terminal of said auto-transformer and said diode anode, a choke coil connected between said source of positive potential and the junction of said condenser and diode, and a cathode ray tube deflection coil connected serially with a second condenser, said serially connected deflection coil and second condenser connected between a point of fixed potential and the junction of said condenser and diode.

6. A sawtooth wave generator comprising, in combination, an auto-transformer having an input and output circuit, said auto-transformer also having a terminal common to said input and output circuits, an uncommon terminal for said input circuit, and an uncommon terminal for said output circuit, said auto-transformer having a step-up turn ratio between its primary and secondary circuits, a thyratron switching device connected between said uncommon input terminal and a point of fixed potential, said switching device consisting of a gaseous discharge tube, a control electrode in said gaseous discharge tube for firing said gaseous discharge tube periodically, a parallel connected resistance and capacity circuit, a source of potential positive with respect to said fixed potential connected to said common terminal through said paral-

1ell connected resistance and capacity circuit, a condenser connected to the uncommon output terminal of said transformer, a diode connected between said common terminal of said auto-transformer and said condenser terminal opposite that connected to the uncommon output terminal of the auto-transformer, the cathode of said diode connected to said transformer common terminal, a choke coil connected between said source of positive potential and the junction of said condenser and diode. 10

7. A sawtooth wave generator comprising, in combination, an auto-transformer having an input and output circuit, said auto-transformer also having a terminal common to said input and output circuits, an uncommon terminal for said input circuit, and an uncommon terminal for said output circuit, said auto-transformer having a step-up turn ratio between its primary and secondary circuits, an electron discharge switching device connected between said uncommon input terminal and a point of fixed potential, said switching device consisting of a gaseous discharge tube, means for firing said gaseous discharge tube periodically and at the beginning of the snap-back time interval of the sawtooth wave, a parallel connected resistance and capacity circuit, a source of potential positive with respect to said fixed potential connected to said common terminal through said parallel connected resistance and capacity circuit, a condenser connected to the uncommon output terminal of said transformer, a diode having a cathode, said diode connected between said common terminal of said auto-transformer and said condenser and having its anode connected to the condenser terminal opposite that connected to the uncommon output terminal of the auto-transformer, the cathode of said diode connected to said transformer common terminal, a choke coil connected between said source of positive potential and the junction of said condenser and diode, and a cathode ray tube deflection coil, said cathode ray tube deflection coil connected serially with a second condenser, said serially connected deflection coil and second condenser connected between a point of fixed potential and the junction of said condenser and diode. 20

8. A sawtooth wave generator comprising, in combination, an auto-transformer having an input and output circuit, said auto-transformer also having a terminal common to said input and output circuits, an uncommon terminal for said input circuit, and an uncommon terminal for said output circuit, said auto-transformer having a step-up turn ratio between its primary and secondary circuits, a thyratron switching device connected between said uncommon input terminal and a point of fixed potential, said switching device consisting of a gaseous discharge tube, means for firing said gaseous discharge tube periodically and at the beginning of the snap-back time interval of the sawtooth wave, and an

inductance connected in series with said gaseous discharge tube for making said gaseous discharge tube conductive only during a portion of the sawtooth wave, a source of potential positive with respect to said fixed potential connected to said common terminal through said parallel connected resistance and capacity circuit, a condenser connected to the uncommon output terminal of said transformer, a diode having a cathode and an anode, said diode connected between said common terminal of said auto-transformer and said condenser terminal opposite that connected to the uncommon output terminal of the auto-transformer, the cathode of said diode connected to said transformer common terminal, a choke coil connected between said source of positive potential and the junction of said condenser and diode, and a cathode ray tube deflection coil, said cathode ray tube deflection coil connected serially with a second condenser, said serially connected deflection coil and second condenser connected between a point of fixed potential and the junction of said condenser and diode. 15

9. A sawtooth wave generator comprising, in combination, an auto-transformer having an input and output circuit, said auto-transformer also having a terminal common to said input and output circuits, an uncommon terminal for said input circuit, and an uncommon terminal for said output circuit, said auto-transformer having a step-up turn ratio between its primary and secondary circuits, a gaseous tube switching device connected between said uncommon input terminal and a point of fixed potential, said switching device comprising a grid controlled thyratron, said grid of said thyratron adapted to receive synchronizing pulses, a source of potential positive with respect to said fixed potential connected to said common terminal through said parallel connected resistance and capacity circuit, a condenser connected to the uncommon output terminal of said transformer, a diode having a cathode, said diode connected between said common terminal of said auto-transformer and said condenser terminal opposite that connected to the uncommon output terminal of the auto-transformer, the cathode of said diode connected to said transformer common terminal, a choke coil connected between said source of positive potential and the junction of said condenser and diode, and a cathode ray tube deflection coil, said cathode ray tube deflection coil connected serially with a second condenser, said serially connected deflection coil and second condenser connected between a point of fixed potential and the junction of said condenser and diode. 25
